W. B. PITKIN,
MOISTENING DEVICE FOR PRINTING PRESSES.
APPLICATION FILED DEC. 17, 1917.

1,335,025.

Patented Mar. 30, 1920.

Walter B. Pitkin, Inventor
by his Attorney
Emery, Booth, Danvers & Harvey

UNITED STATES PATENT OFFICE.

WALTER B. PITKIN, OF NEW YORK, N. Y., ASSIGNOR TO PLANOGRAPHIC EQUIPMENT COMPANY, INCORPORATED, OF NEW YORK, N. Y., A CORPORATION OF NEW YORK.

MOISTENING DEVICE FOR PRINTING-PRESSES.

1,335,025.

Specification of Letters Patent. Patented Mar. 30, 1920.

Application filed December 17, 1917. Serial No. 207,449.

To all whom it may concern:

Be it known that I, WALTER B. PITKIN, a citizen of the United States, and a resident of the city, county, and State of New York, have invented an Improvement in Moistening Devices for Printing-Presses, of which the following is a specification.

My present invention relates to apparatus of the general type shown and described in my co-pending application, Serial No. 207,448, filed on the same date as this, in which a printing surface, such as a planographic or lithographic or other plate, is moistened by the application of steam applied through a series of jets, which case I have designated as Case A; and also my other parallel pending application, Serial No. 207,451, filed on the same date as this application, which I call Case C.

In general, the two applications referred to contemplate respectively the use of steam derived from an outside source, and the use of a tank of water which is brought to boiling point, by preference by an inside heating apparatus; as I have explained in one of these cases, I consider vapor of any suitable liquid as within the scope of those applications, as I do of this. The present case, which I call Case B, however, embraces features of novelty not shown in those in that it provides means operating without physical contact for sealing the moistening tank, which is placed adjacent to the impression cylinder of the press; that is, without physical contact between the plate on the rotating cylinder (or other impression device) and the sealing means. The plate which I have especially in mind (although my invention applies to any form of printing device in which the paper, or type face of whatever kind may be selected, may be dampened in order to get a good impression) is a zinc or aluminum plate or process cut, and especially the type of plate now known in the trade as "planographic." In these, as is generally known, an ink receiving design is formed by the use of certain classes of asphaltic compound which are sufficiently rigid to maintain all of the points and lines necessary for the design and to transfer the ink properly to the paper, but which do not

resist abrasion from any form of sliding contact without impairing the printing quality.

My present invention, therefore, contemplates a printing or impression cylinder carrying the plate-moistening means adjacent thereto, and sealing means for the closure between the printing cylinder and the moistening means, operating to maintain a substantially complete seal without physical contact between the plate and the sealing means; and at the same time a means is provided for producing a rapid condensation and cooling upon the printing surface and for the removal of globules and surface water, through the application of air seals to the closure between the moistening device and the tank. One of the means which I have illustrated is a series of air-jets disposed adjacent to the closure, the air being directed against the opening at a pressure sufficient to counter-balance any pressure which may be generated within the moistening tank. Other means consists of forming the edge of the moistening tank in such a way as to make an air dash-pot effect, preferably by forming a series of square shouldered longitudinal grooves in the abutting edge or surface of the tank where it adjoins the cylinder. It is of course contemplated that this closure shall be made as narrow as possible so that the plate may pass the same with the least possible margin. The accompanying drawings show,

In Figure 1 a sectional view, partly diagrammatic, of my improved moistening device,

Fig. 2 a plan of the parts shown in Fig. 1.

Fig. 3 a detail of a method of forming the closure of the tank with a pneumatic dash-pot.

Fig. 3^a an alternative form of the latter. 95

It will be understood that my invention is applicable to various forms of printing presses and that it is not necessarily limited to a press carrying the forms upon a cylinder, although I have illustrated my invention in connection with an off-set press; and it will also be understood that the specific form of my invention illustrated in the drawings and described herein may be

greatly varied, without departing from its essential principles or the spirit of my invention, the drawings being illustrative merely of an operative form of my device 5 and indicating one of the many ways in which it may be applied.

Referring to Figs. 1 and 2 of the drawings, 1 indicates a form cylinder, that is, the cylinder which carries printing surfaces, whatever their nature, such as planographic plates, etc., and which is inked by suitable inking apparatus indicated in the drawings by the ink roller 2. The form cylinder engages the offset cylinder 3, which 10 may carry the ordinary rubber blanket, and which in turn co-operates with the web 4 taken from the roll 5. The direction of rotation of the form cylinder 1 is indicated by the arrow 6.

20 Located adjacent the form cylinder and in close proximity to the plates thereon is a housing 7, which preferably conforms to the curvature of the cylinder 1, at one of its sides. The housing 7 is provided with 25 means for introducing steam into the interior thereof, which means may be the jets 8 supplied by the steam pipe 9. The steam pipe 9 is provided with a suitable steam cut-off and regulating apparatus, such as the 30 globe valve 10. The steam jets 8 are mounted radially to the form cylinder 1 and are thus directed toward the face of the plate upon the cylinder 1. They may be adjusted toward and away from the plate by any suitable 35 adjusting apparatus such, for instance, as the yoke 11, which is turned upward at each end and extends across the width of the housing. The steam pipe 9 is attached to the upturned ends of the yoke and the 40 ends of the yoke are prolonged so as to cover the slots 12, within which the steam pipes move. Thumb screws 13 are provided for moving the yoke. They are held against longitudinal movement in the yoke 11 and 45 are in threaded engagement with the boss 14 mounted upon the housing 7. By means of jets 8, steam may be directed against the plates of the cylinder 1 at a velocity and under a pressure sufficient to cause it to 50 penetrate the minutest depressions in the plate 1 and to thus effectively moisten it.

Owing to the relatively large mass of the cylinder 1, condensation of the steam to some extent takes place, thus covering the 55 plate with water. Mounted upon the housing 7 are the air jets 15, preferably arranged to discharge upon the surface of the plate as it leaves the housing 7, due to the rotation of the cylinder 1, and pointed in a direction 60 substantially tangential to the cylinder 1. The jets 15 preferably discharge, as shown in Fig. 1, into the opening between the upper edge of the housing 7 and the cylinder 1. The discharge of air thus causes a 65 rapid condensation of the steam upon the

plate, by rapidly conducting the heat away from the plate and performs a number of other functions, among which are, preventing the steam from escaping from the housing 7, by driving it back into the housing, 70 cooling the plate, removing any globules or air bubbles which may be adhering to the plate, distributing the water of condensation over the surface of the plate, removing any surplus water of condensation and 75 causing the water to flow over the plate, thus effectively covering any portions of the surface, to which water has not adhered. The jets 15 may be of any suitable size and shape, and are preferably arranged at intervals across the entire width of the plate. They may be directed at any suitable angle or at varying angles with respect to the longitudinal axis of the plate or direction of rotation of the cylinder, and are supplied 80 with compressed air at suitable pressure, through the pipe 16, which is supplied with a regulating valve 17 and is connected with any suitable source of air pressure.

The pipe 16, carrying the jets 15, may be 85 adjusted toward and away from the cylinder 1 and housing 7 by any suitable means, such as the adjusting screw 18, which is in threaded engagement with the arm 19, carrying the pipe 16. Arm 19 is hingedly 90 mounted, as at 20, upon the housing 7.

Located below the housing 7 is a trap 21, which is adapted to catch any surplus water of condensation.

The operation of my improved device is 100 as follows: Steam is fed to the apparatus through the steam pipe 9, discharging through the jets 8 upon the plate and filling the interior of housing 7 with the steam, at substantially atmospheric pressure. The 105 rotation of the cylinder 1 carries the plate, which has been subjected to the action of the steam, into the zone of action of the air jets 15, which causes a rapid condensation and a spreading of the water over the plate, 110 which has been described above. Any surplus water will run down into the housing 7 or trap 21, from which it may be drawn.

In Figs. 3 and 3^a, I show a means of making the seal between the tank 7 and the cylinder 1 by means of a pneumatic dash-pot. It is obvious that the forms of closure here shown may be employed in connection with the air-jets 15, if desired; or under suitable conditions they may be employed alone. It 120 is further obvious that this form of construction may be used with the devices shown in my parallel pending applications already referred to in this case, and I do not by the claims made mean to exclude such modifications. In the figures now referred to, 7 is as before the tank in which the water-vapor or steam is contained or generated. The exit wall of this tank is shown as expanded at 22 into a lip wherein are disposed 125 130

rectangular groove 22^a; these are by preference interrupted at intervals by partitions 22^b. This lip may be conveniently formed of a single casting and only the portion of it adjacent to the cylinder needs to be finished, the finished surface being concentric with the impression cylinder, and as close to the plate as possible. The effect of the grooves is to cause eddies due to the motion of the air or steam under the pressure in the tank, and also from the centrifugal force imparted to it by the rotation of the cylinder, the steam or vapor being entrapped in the slight recesses in the design on the plate, escaping into the grooves 22^a, and there setting up eddies which create a back pressure, as is understood. No similar device is needed in connection with the closure upon the other side of the tank, though it might be used if desired; because the motion of the cylinder is inward toward the tank and centrifugal force will ordinarily suffice to prevent the exit of steam or vapor, in conjunction with the trough 21 already referred to.

In Fig. 3 I have shown another shape for the grooves of the pneumatic seal. In these the lower or entering wall 23 of the groove is formed at a slight angle, so that steam or vapor may more conveniently enter the groove where it will set up a rotary movement creating a back pressure against the wall 24. Of course other forms of grooves may be used and the invention may, in this respect as in others, take many forms.

What I claim is:

1. A moistening device for printing presses comprising, in combination with a printing plate, means for first subjecting the plate to steam and then subjecting it to an air blast.

2. A moistening device for printing presses comprising, in combination with a printing plate, means for first subjecting the plate to steam throughout substantially its entire width and then to a plurality of blasts of air, at intervals, throughout substantially its entire width.

3. In a device of the kind described, a rotatable form cylinder, a printing plate mounted thereon, a housing in close proximity thereto, means for introducing steam into the housing, and means for subjecting the plate to a blast of air as it leaves the housing, during the rotation of the cylinder.

4. In a device of the kind described, a rotatable form cylinder, a printing plate carried thereby, a stationary housing inclosing a portion of the surface of the cylinder, means for introducing steam into the housing and means for subjecting the plate to a blast of air at a plurality of points as it leaves the housing, during the rotation of the cylinder.

5. In a device of the kind described, a rotatable form cylinder, a printing plate

carried thereby, a stationary housing inclosing a portion of the surface of the cylinder, a plurality of steam jets located within the housing and discharging toward the plate, and a plurality of air jets discharging 70 toward the plate, outside of the housing and adjacent thereto.

6. In a device of the kind described, a rotatable form cylinder, a printing plate carried thereby, a stationary housing inclosing a portion of the surface of the cylinder, a plurality of steam jets located within the housing, adapted to discharge steam 75 in the direction of the plate and adjustable toward and away from the plate, and a plurality of air jets located outside of the housing, adapted to discharge air toward the plate, and means for adjusting the position of the air jets with respect to the plate.

7. In a device of the kind described, a 85 rotatable form cylinder, a housing having one side conforming to the shape of the cylinder and in close proximity thereto, means for introducing steam into the housing and means, external to the housing, for directing a blast of air between a portion of the housing and the cylinder.

8. In a device of the kind described, a form cylinder, a printing plate mounted thereon, means for directing a plurality of 95 jets of steam toward the plate, in a direction substantially radially to the cylinder, and means for directing a plurality of jets of air toward the plate substantially tangentially to the cylinder.

9. In a device of the kind described, a form cylinder, a printing plate mounted thereon, a housing in close proximity to the plate, means within the housing, for directing a plurality of jets of steam toward the 105 printing surface of the plate, in a direction substantially radially to the cylinder, and means, external to the housing, for directing a plurality of jets of air toward the printing surface of the plate, in a direction substantially tangentially to the cylinder.

10. In a device of the kind described, a rotatable form of cylinder, a printing plate mounted thereon, a housing in close proximity thereto, the housing containing steam 115 or vapor, and means for closing the opening between the housing and the cylinder without physical contact between them.

11. In a device of the kind described, a rotatable cylinder and a printing plate 120 mounted thereon, a housing in proximity to the cylinder containing steam or vapor under pressure, means for creating a back pressure between the cylinder and the edge of the housing necessary to prevent the escape of 125 the steam or vapor.

12. In a device of the kind described, a rotatable cylinder having a printing surface carried thereby, a housing adjacent to the cylinder and containing steam or vapor, and 130

a pneumatic seal maintaining the closure between the housing and the printing surface.

13. In a device of the kind described, a
5 rotatable cylinder having a printing surface carried thereby, a housing adjacent to the cylinder and containing vapor or steam, and a pneumatic seal maintaining the closure between the cylinder and the exit wall of the
10 housing.

14. A moistening device for printing

presses comprising, in combination with a printing plate, means for dampening the plate, and means for removing surplus water therefrom, comprising means for subjecting 15 the plate directly to the separate and successive action of steam and of an air blast.

In testimony whereof, I have signed my name to this specification this first day of December, 1917.

WALTER B. PITKIN.
